United States Patent Office.

HENRY J. KING AND BENTON L. BEEBE, OF MIDDLETOWN, NEW YORK.

Letters Patent No. 97,779, dated December 14, 1869.

IMPROVEMENT IN HYDRAULIC ENGINES.

The Schedule referred to in these Letters Patent and making part of the same.

To all whom it may concern:

Be it known that we, HENRY J. KING and BENTON L. BEEBE, of Middletown, in the county of Orange, and State of New York, have invented a new and improved Fluid or Gas-Engine; and we do hereby declare that the following is a full, clear, and exact description of the construction and operation of the same, reference being had to the accompanying drawings, making a part of this specification, in which—

Figure 1 is a front view.

Figure 2 is a side view.

Figure 3 is an interior view, in detail, of rectangular box, showing valves and valve-chamber.

Figure 4 is a transverse section of rectangular-box, taken in the plane $x-x$ of fig. 3.

Figure 5 is a view in detail of valve.

Figure 6 is a longitudinal section of rectangular box.

Figure 7 is a sectional view of piston-box or cylinder, showing piston with air-chamber.

Like letters in the different figures of the drawings indicate like parts.

Our invention has reference to a fluid or gas-engine, to be used for hoisting-purposes, or as a small motive-power for running printing-presses, sewing-machines, and other light machinery, where it will not pay to use steam; and consists of a rectangular box, provided with valves and a valve-chamber, in combination with the piston-boxes or cylinders, having the pistons thereof provided with air-chambers, the said valves being operated upon and regulated in their action by a slotted slide embracing the shaft of the fly-wheel, and having an arm, by which it connects with one or more levers, connecting with the stem or rod of the valves, in combination with an elongated cam, attached to the shaft, the said slide being so constructed and operated upon by the cam as that the valves will be given a "quick motion" when the piston is at the end of each stroke, thus permitting of the valves being operated the same either way, and thereby enabling the engine to be completely reversed, so that it can be used to a great advantage for hoisting-purposes.

A is the rectangular box.

B is the valve-chamber, formed longitudinally in the centre thereof by partitions and upper plates α , with suitable packing over the latter, to make valve-chamber water-tight where the top plate of the box fits down on plates α . These partitions and plates extend not quite to the ends of the box, in order to leave a passage-way for the water around the ends of the valve-chamber, the water being admitted through supply or inlet-pipe C, direct to the valve-chamber, and passing from thence to exhaust or outlet-pipe b; the former being attached to and extending through the side of the box to one of the partitions; the latter

being attached to the bottom, opposite and between the other partitions and side of the box.

D D are the valves, having their edges next to the sides of the valve-chamber formed with recesses to receive pieces fitting therein, and having rubber springs intervening between them and the shoulders of the recess, so as to keep the pieces pressed against the sides of the valve-chamber, and thus make the valves water-tight, the valves being placed on the rod or stem e with screw-threads thereon, and fastened thereto by washers and screw-nuts d d. The rod, in passing through the end of the box, is made water-tight by the packing-box e.

E E are the piston-boxes, bolted or otherwise fastened to the top plate of box, the plate having openings f f, for the admission of the water from valve-chamber to the piston-boxes, the latter having an orifice, g g, in each box, closed by stop-cocks, whereby the valves may be lubricated with oil when required.

F F are the pistons or plungers, being similar to one cylindrical vessel placed within another, with bottoms upward.

These pistons are, in depth, a little above the boxes which enclose them, when down on the bottoms thereof, and have a space divided off in the centre of each piston by partitions, which extend across, and are closed at the bottom, thus forming the air-chambers h' h', and, at the same time, receptacles for the piston-rods h h, which are secured at the bottom of the spaces to pivots extending through partitions and rods, the spaces being of sufficient width to allow the rods a free play therein.

The bottom of the spaces, or what might be termed the trunk of the pistons, serves, in connection with the elastic nature of the air, to break the force of the water rushing into the boxes or cylinders E E, so as to give an easy and regular motion to the pistons.

The pistons are made water-tight by a ring of rubber surrounding them, and having a flange fitting down in between them and the boxes, and secured by a metallic collar, with flange bolted down on it to the flange of the boxes or cylinders.

The piston-rods are suitably connected with cranks G G, attached rigidly to the ends of the shaft, which has its bearings in journal-boxes, attached to the heads of the standards H H, the fly or band-wheel being secured to the shaft about the centre between the piston-rods.

I is the slotted slide, the slot being of sufficient width for the purpose of allowing slide to be slipped on over the shaft, and of its having a free up-and-down motion thereon, the end of the shaft extending beyond the standard. This slide has V-shaped shoulders or projections i i at the upper and lower ends thereof.

An elongated cam, *J*, tapering somewhat to a point at the end, is also placed on over the shaft against the slide, so as to impinge against the shoulders of the slide, the cam being so attached to the shaft as to have a little play thereon, and thus not strike the shoulders too abruptly. A washer is placed against the cam, and the crank against the washer, so that the crank will be sufficiently off from the shoulders as not to rub them while revolving.

The slide is supported by two guides, *k k*, fitting and working in boxes *m m*, projecting from the sides of the standards. An arm, *n*, projects from the lower end and side of slide, to which is pivoted an arm, *o*. At the lower end of arm *o*, and connecting therewith by a pivot-bolt with screw-nut, is a lever, *p*, which is supported by the fulcrum *q*.

Projecting downward from this lever *p*, in a line with the pivot-bolt, which secures lever *p* to the fulcrum, is a short arm, *r*, connecting with the end of lever *s*, supported in a guide-box *u*, the lever *s* being so constructed as to make a turn at right angles, or have a crank connect it with the end of valve-rod, being fastened thereto by a screw-nut.

The object of the slide and cam, as will be obvious, is, on every alternate stroke of the pistons, the cam impinging against the V-shaped shoulders of the slide, causes the valve-rod to operate valves *D D* through the arms and levers described, connecting rod with slide, so as to regulate properly the admission of the water to each piston-box or cylinder, and as will also be obvious, the V-shape of the shoulders of the slide enables the valves to be readily reversed, so that the engine may be worked as well one way as the other.

One great advantage is the facility with which this engine can be made to run by gas, by placing a third valve or cut-off on the same valve-stem or rod with

the other two valves, the valve being flat, with a slot in it to admit the gas through the supply or inlet-pipe when sliding by the same; and by arranging an electric battery to ignite the gas under the cylinders, we can run it by gas, thus making a fluid or gas-engine, and by having an indicator attached, can measure the same as it passes through the engine.

Having thus fully described our invention,

What we claim therein as new, and desire to secure by Letters Patent, is—

1. The rectangular box *A*, provided with valve-chamber *B*, valves *D D*, inlet and outlet-pipes *C b*, in combination with piston-boxes *E*, having the pistons provided with air-chambers *H*, substantially as set forth.

2. The rectangular box *A*, with partitions and plates *a a*, valves *D D*, rod or stem *c*, packing-box *e*, inlet and outlet-pipes *C b*, constructed and arranged substantially as set forth.

3. The pistons *F*, so constructed with air-chambers as to form a trunk, extending to the bottom end thereof, in combination with valves and valve-chamber, substantially as set forth.

4. The slide *I*, provided with V-shaped shoulders *i*, and connecting by levers with valve-rod or stem *c*, in combination with elongated cam *J*, substantially as set forth.

5. The elongated cam *J*, so arranged with slide, as to impinge against either side of the shoulders *i* thereof, and operate the valves, substantially as and for the purpose set forth.

HENRY J. KING.

BENTON L. BEEBE.
